BUILDING TOY

Robert G. Mote, 1132 Queens Ave.,
Yuba City, Calif. 95991
Filed Feb. 10, 1964, Ser. No. 343,721
5 Claims. (Cl. 46—25)

This invention relates to a building toy for young children comprised of structural units which interfit together in numerous and varied ways. More particularly, the invention relates to such a toy in which the structural units are preferably made from empty milk cartons of the waxed cardboard variety.

It is common knowledge that small children, particularly those in the age group from about 2 to about 8 years, derive much useful benefit from building toys made up of structural units which can be variously assembled or interfitted together to form simulated buildings or other structures. In addition to directly benefitting the children by helping to develop and improve their mental and manual skills, such toys indirectly benefit their parents and others charged with the responsibility of raising or caring for them by helping to keep the youngsters occupied and out of mischief for substantial periods of time.

Much of the milk sold at retail is dispensed in waxed cardboard containers (hereinafter, for the sake of brevity, referred to as milk cartons or simply cartons), typical of which are the 1- and 2-quart milk cartons commonly seen in supermarkets and other grocery stores. These cartons are presently classified and treated by seller and buyer alike as "throwaway" containers of the same category as empty tin cans, beer bottles, etc. I have now discovered a means of converting such cartons into structural units suitable for the building toy purposes of this invention. The advantages of this are two-fold; namely (1) the conversion of a heretofore useless discard product into a useful item, and (2) the provision of a new and useful toy.

It is thus a principal object of this invention to furnish a new and useful building toy.

It is a more specific object of the invention to furnish a means of converting used milk cartons, presently substantially worthless discard items, into useful toy products.

Other objects, features, and advantages of the present invention will become apparent as the description thereof proceeds.

My toy structural units can be made in various ways, one such being the cutting of milk cartons to appropriate shapes as taught herein and illustrated in the accompanying drawings. The structural units, whether of milk carton or other origin, are characterized by cooperatively mating features permitting them to be assembled into structures of a great variety of sizes and shapes. The choice of structural variety thereby afforded is virtually without limit, except for such inherent limitations as are imposed by the shapes of the structural units themselves. This feature of the invention permits the child to give full rein to his imagination and contributes substantially, it is believed, to the utility of the invention.

The substance and scope of the present invention will be better understood by reference to the accompanying drawings, of which:

FIGURE 1 is a perspective view of a possible assembly of structural units exemplary of the units of this invention;

FIGURE 2 is a view of the assembly, mostly in section, taken along line 2—2 of FIGURE 1;

FIGURE 3 is a fragmentary sectional view of the assembly taken along line 3—3 of FIGURE 1;

FIGURE 4 is a perspective view, with hidden-line delineation of certain features not otherwise visible, of a structural unit in accordance with this invention;

2

FIGURE 5 is a perspective view, with hidden-line delineation of certain features not otherwise visible, of another structural unit in accordance with this invention;

FIGURE 6 is a perspective view, with hidden-line delineation of certain features not otherwise visible, of still another structural unit in accordance with this invention;

FIGURE 7 is a perspective view, with hidden-line delineation of certain features not otherwise visible, of a structural unit in accordance with this invention having end flap means for interlocking connection with another unit having cooperating end flap means.

A detailed description of the drawings follows, throughout which the pictured embodiments of the structural units are described in language consistent with milk carton origin of the units. This technique is, it is believed, conducive to a better understanding of the design geometry of the involved parts, but it should not be inferred from its use that my structural units are necessarily of milk carton origin, since, as previously indicated, they can be prepared from any suitable source material. The important criteria are the shapes and relative sizes of the units, not their genetic histories. There are, however, some preferences as to choice of materials of construction, and these will be discussed in greater detail hereinafter.

Turning now to a consideration of the drawings, it is first pointed out that all of the structural units depicted are of square cross-section and equal cross-sectional area. It is not essential, however, that the cross-sectional areas of the units be equal, and they can vary in this respect if desired. For example, it is within the functional realm of the invention to form assemblies of structural units configured as taught herein, but sized consistently with both quart and half-gallon, or other capacity, milk carton derivation.

For the most part, as the drawings show, my toy structural units fit, and are held, together to form the various assemblies of the invention at a plurality of points by male and female coupling means. The coupling means comprise snugly interfitting male members and receptive female members so disposed as to permit connective relationship between the units in fulfillment of the purposes of the invention. The definitive geometry of the co-operating male and female parts of my structural units is unique in my experience, and permits connective assembly of the units in a way hitherto unknown insofar as I am aware.

The male and female features of my structural units are each reducible to one of three basic forms, here considered, for the previously discussed reasons, in a context assumptive of derivative mutilation of milk cartons. In this connection, the preferred milk cartons for conversion to structural units in accordance with the teachings herein are those of the conventional rectangular parallelepiped shape, and, to resort to redundancy for the sake of emphasis, having flat ends. However, as will eventually be apparent, milk cartons of other shapes, (so long as they have square cross-sections) are equally applicable for the indicated purpose, exemplary of such cartons being those with gabled pouring ends of the type familiar to all.

While, as will by now be more than evident, a preferred way of making my novel building units is by carving them out of empty milk cartons, it is within the spirit and scope of the invention to manufacture the units directly from appropriate starting materials, or otherwise make or contrive them. There is nothing critical about the materials of construction for the units aside from the obvious necessities occurring to one familiar with the invention. Some suitable materials will, because of certain properties, be preferred over other equally suitable ones, but in general

almost any solid material will suffice. Preferred materials, other than the aforesaid waxed cardboard, are plastics, hard rubbers, wood, thin plate metals, etc.

Proceeding now to the specifics of the male and female coupling features of my toy building units, the three configurational variants above adverted to are: (1) a transverse notch cut through the milk carton, two examples of which are shown at 1 and 3 on the FIGURE 4 unit, herein-after referred to simply as the notch cut; (2) a transverse notch cut in two dihedral side walls of a milk carton, as shown at 5 on FIGURE 7, herein-after referred to as the single side-notch cut, and; (3) a hole in one side wall of a milk carton, equal in shape and size to half of the wall opening of a single side-notch cut (such a hole being shown at 7 in FIGURE 6), herein-after referred to as the half-notch cut.

The notch cut is V-shaped in profile, sloping inwardly from points on a line passing perpendicularly through the longitudinal axis and two diagonal corners of a milk carton to dihedral intersection at the oppositely diagonal corners of the carton. The dihedral points of the notch cut on said oppositely diagonal corners of the milk carton fall on a line perpendicular to the longitudinal axis of the carton, and the angle of intersection of the sloping planes delineative of said notch cut intersect at an angle of 90°. This angle permits straddling interfit between the notch cut of one unit and a dihedral corner of another unit, as well as mating relationships with units having single side-notch and half-notch cuts, as will presently be explained. The notch cut results in the formation of two ears of right triangular pyramidal shape projecting outwardly from the valley of the cut and terminating in apices disposed at opposite diagonal corners of the carton, as shown at 9 and 11 on FIGURE 4. It will, of course, be apparent that only two of the pyramidal walls of each ear are real, the third one, in each instance, being merely an imaginary planar surface coexistent with the sloping lines of the cut in the appropriately situated walls of the milk carton. This is not to say that ears having all finite walls, or even completely solid ears, are without the scope of this invention, since, as will be seen, all such are clearly within its functional capabilities.

The single side-notch cut is of a V-shaped profile, extending half-way through a milk carton in the transverse direction, with the open end of the V disposed along a first dihedral corner thereof, and the closed end of the V co-existent with a line perpendicularly disposed with respect to the axis of the carton, and joining the two dihedral corners nearest said first dihedral corner of said carton. The V-shape of the single side-notch cut has a channel angle of 90°, thereby permitting a structural unit with such a cut to snugly cradle a second structural unit in perpendicularly transverse relationship thereto, with the dihedral corner of the latter in mating repose within the channel groove of said cut. In addition to permitting the described cradling relationship, the single side-notch cut is of precisely the right size to snugly receive the notch-cut end of a structural unit so defined. When making the suggested insertion, the tips of the ears of the notch-cut of the latter or male unit should be so oriented as to enter the single side-notch cut of the other, or female, unit at its widest, as seen in profile, end. When the ears of the male unit thus oriented are pushed through the side-notch cut opening in the female unit to their fullest extent, they abut the inner walls of the latter in matingly cooperative relationship. FIGURE 1 shows two male units, 13 and 15, with notch cut ends fully inserted into two female units, 17 and 19, with single side-notch cuts respectively, in the above-described manner, and FIGURE 3 illustrates the resulting mating interfit between the ears of male unit 15 and the inner walls of female unit 19.

The male and female structural features making it possible to couple my units together in the above-indicated way are preferably so sized as to assure a relatively tight fit therebetween, although not so tight as to make it diffi-

cult for small children to put the units together and take them apart again. Structural units with optimum male and female tolerances are made with relatively little difficulty from hollow starting materials such as empty milk cartons. It is again emphasized, however, that my toy structural units can be made from materials other than empty milk cartons or the like. It is even within the scope of the invention to provide such units of solid, rather than hollow, construction, except for the necessary openings and internal hollows of the proper sizes and shapes to satisfy the requirements taught herein. It is also within the scope of the invention to utilize structural units of mixed hollow and solid construction, so long as they are designed to interfit in a manner, and thus perform functions in accordance with this invention.

It is not essential that the subject male and female parts be as closely tolerant as their preferred status requires, and they may fit loosely within the bounds of the invention since many structural assemblies are still thereby achievable.

The half-notch cut, as previously indicated, and as the name implies, is the equivalent of half of a single side-notch cut occurring in either one of the dihedral carton walls penetrated by the latter. This manner of description is employed as a technique to more easily and quickly paint a verbal picture of the visual interrelation of the two involved types of cut, and hence, it is hoped, promote faster and keener sensual appreciation thereof. In functional reality, however, the half-notch cut is entirely different from, rather than merely a fractional part of, the single side-notch cut, as will soon become apparent. The primary function of a half-notch cut is to serve as a receptive opening for one of the ears of a structural unit with a notch cut, and thereby provide another means of coupling my units together.

To couple a unit with a notch cut to one with a half-notch cut, one ear of the former is inserted into the half-notch cut of the latter as far as it will go to an angle of about 45°, as measured between the axis of the carton with the notch cut (male unit) and the plane of the wall of the other carton (female unit) dihedral with the wall pierced by the half-notch cut and adjacent the wide end of said cut. When the male unit is thus partially inserted into the female unit, a symmetrical portion of the former, including one ear and an integrally adjacent segment in the mirror-image shape of said ear, is engulfed in the cavity of the latter. The fully inserted ear of the male unit bears flatly, around its notch-cut edges, against the inner surface of the wall of the female unit previously identified as that dihedral with the wall penetrated by the half-notch cut and adjacent the wide end of said cut, and the dihedral corner of the male unit extending from the tip of its inserted ear is snugly cradled in the V-shaped peripheral edges of the half-notch cut converging from its wide end. The tip of the inserted ear extends inside the female unit approximately to the line of intersection between the wall against which said ear bears and the wall opposite and parallel to that penetrated by the half-notch cut.

The described interfitting relationship will be better understood by reference to the drawings, which show, in FIGURE 6, the wide end 21 of a half-notch cut in a female unit and a wall 23 of such a unit against the inner surface of which the ear of a male unit bears when the two units are coupled in the manner here taught. The drawings further show, in FIGURES 1 and 2, an eared male unit 25, inserted to the fullest extent in a female unit 27, FIGURE 2 revealing, at 29, the abutting relationship between the ear of the former and the appropriately adjacent inner wall of the latter.

In addition to the interfitting features of my structural units so far described, there is an additional one within the compass of the invention, this being an interlocking means for holding the units together in end-to-end relationship. Basically, the interlocking means comprises two or

more, but preferably two, pairs of cooperating semi-circular flaps, each pair representing two units and each flap being sprung outwardly to a sufficient extent (but only to such an extent) to permit insertion of its cooperating counterpart flap thereunder. It will be apparent that here, as in the case of the other interlinking features of this invention, any number of structural unit combinations can be adapted to interlock in the prescribed manner, there being nothing critical about the number of pairs of such interlocking units. Also, and this is equally applicable to all pairing or interlinking variants taught herein, there can be any possible number and variety of other interfitting or coupling features present on structural units incorporative of the presently-described fastening flaps. It is sufficient, for purposes of this invention, if some of the involved structural units have at least some of the mating male and female features taught herein, and it is immaterial how and to what extent those features are distributed or scrambled on the individual units themselves. For example, a structural unit can be of wholly male character, such as that of FIGURE 4 (notch-cut on both ends) or FIGURE 5 (notch-cut on one end only); of wholly female character, such as those shown in FIGURES 6 and 7, or units having two or three single side-notch cuts each; or of hermaphroditic character, having both male and female features.

Turning again to the subject of the end-to-end fastening means for the structural units, the preferred spacing arrangement for the involved semi-circular flaps is one of symmetry along a diagonal of the square unit end, with each flap describing an arc segment of the same radius around a center located on the diagonal. Two flaps, such as described, are shown at 31 and 33 on FIGURE 7. It will be observed that the flaps extend in mutually opposite directions from the diagonal on which their arc centers are located, the reason for which will be apparent from an understanding of the manner in which they cooperate with flaps on other units to perform their interlocking function. To interlock two units in accordance with present teachings, their ends are placed flatly together with their flaps so positioned as to each ride under a complementary flap on the stranger unit when said units are twisted in appropriately opposite directions, and then so twisting said units until each flap rotates under the uncut portion of the circle of its cooperating flap on the stranger unit. At the completion of the twisting motion, the two structural units are joined endwise in substantially perfect alignment, and are presented from relative longitudinal movement by the underlap of each of its flaps with the uncut portion of the circle of a counterpart flap on the other unit. To unlock the two units, they are simply twisted until the flap fastenings disengage.

It should be emphasized that the number and pattern of disposition of the aforesaid flaps on my structural units, and even the shape of the flaps, can vary in numerous ways within the scope of this invention. However, the flap pattern and other related particulars should be substantially the same on all units intended for mutually reciprocal end engagement if proper interlocking of the units is to be achieved. Thus, for example, corresponding flaps on separate units must extend in the same relative directions from their arc centers, rather than in opposite directions, as will be demonstrably evident from any attempt to engage two units with oppositely extending flaps. Finally, as FIGURES 2 and 7 illustrate, the flaps on opposite sides of the center of any common line therethrough (typically a diagonal of the square end of a structural unit) extend in opposite directions, respectively, from said line. The reason for this will be apparent from an understanding of the manner in which the subject interlocking means functions.

An optional feature of my invention is the provision of intermediate longitudinal slots, which may be wholly or partially V-shaped, in the sloping end edges of the ear walls of notch-cut units, as illustrated by FIGURE 5. The

purpose of such slots is to increase the interlinking versatility of the involved notch-cuts. Various other modifications of a similar character which contribute to greater functional adaptability of the structural units without countervailing their basic character or integrity are also optional and within the contemplated bounds of my invention.

FIGURE 1 shows one of the many possible assemblies, or aggregative structures, which can be built from the structural units of this invention. While the FIGURE 1 structure is of relatively uncomplicated character by comparison with any of the almost infinite number of substantially more complex structures possible of achievement with my structural units, it is felt to be sufficiently inclusive of the various interfitting and interlinking means encompassed by the present invention to comprehensively teach the fundamentals requisite thereto.

Considering FIGURE 1 now in greater detail, the lowermost support member of the pictured structure is a vertically disposed unit 34 having a flat base which rests upon a supporting surface (not shown) and a notch cut defining the shape of its upper end. Unit 35 supports the two previously mentioned female units 17 and 19 in transverse cradling relationship as shown, said units being joined end to end by flap fastening means such as those formerly described and illustrated at 31 and 33 on FIGURE 7. Female units 17 and 19 in turn support two male units 13 and 15, which are inserted respectively therein in the manner shown and previously described in detail. From FIGURE 1, considered in conjunction with FIGURES 2 and 3 and the foregoing descriptive material, the interfitting relationship and orientation of each unit relative to pertinent others is clear. In this connection, it will, of course, be evident that interconnected units 13, 15, 17 and 19 are, of necessity, supported by unit 35 at their midpoint of symmetry, which occurs at the plane of end-to-end interlock of units 17 and 19. The necessity for this midpoint's support, occasioned by the obvious need for balance in the structure, demonstrates one child training factor inherent in my building toy, this being a requirement for sound design judgment if successful completion of a self-supporting structure to be achieved, and the consequent improvement in the abilities requisite to such design judgment (as well as design skills in general) which continuous use of the toy engenders.

Disposed in direct vertical alignment above unit 35, is another unit 37 having a notch-cut configuration at each end and being similar in appearance to the FIGURE 4 unit. The notch cut in the lower end of unit 37 straddles the midpoint of end-to-end joined units 17 and 19 in such fashion that the tips of its defining ears meet the upwardly extending tips of the ears on unit 35. Cradled in the upper notch cut of unit 37 is a female unit 27, of previous discussion, with a half-notch cut in its forwardly facing upper side. The two notch cuts in unit 37 are diagonally corresponding (so that both are simultaneously silhouetted against a common planar background) and female unit 27 reposes in the upper notch cut in parallelism to the co-extensive axes of end-connected units 17 and 19. Partially inserted within the half-notch cut in unit 27 is a male unit 25 marking the peak of the structure.

I have fashioned a number of my structural units from empty milk cartons and have made numerous structures having shapes suggestive of animals, robots, etc., therefrom, as well as many aggregative assemblies suggestive of nothing in particular, but requiring imagination, skill and patience to complete without mishap. More importantly, I have permitted young children, my own as well as others, to play with the milk carton units, as a result of which I noticed that they remained preoccupied for relatively long periods of time, assembling and reassembling the units into structural combinations of numerous and varied shapes and sizes.

Four configurational features of my structural units

contributive to interfiting or interlocking relationship therebetween, namely, the notch cut, the single side notch-cut, the half-notch cut and the end flap fastening means, have been described in detail hereinabove. While each of these features makes a significant contribution to the substance of my invention, I wish to make it clear that the invention does not depend upon the concurrency of all four of them for its existence. Thus, the absence of one or more of the features from a set of structural units otherwise within the definitive limits of the invention does not necessarily render the set inoperative to the point of non-includability within those limits. This does not mean, however, that any combination of two or more of the four features in a set of structural units is a ticket to such includability of that set. Thus, there are certain combinations of features so barren of potential productivity as to yield nothing of patentable merit, such as, for example, those found in sets of wholly female structural units characterized only by single side-notch and half-notch cuts. In contrast, there are other combinations of features of relatively high potential productivity, such as sets of structural units incorporative of both male and female features in such number and manner of distribution as to assure many aggregations of interfiting parts.

As will by now be apparent, the number of possible combinations of structural units of the various types taught herein is legion, of which those combinations within the scope of this invention are likewise legion. Whether or not a combination is within the latter category depends upon a number of factors, including the number of units involved, the number of types of interfiting or interlocking features present, the manner of distribution of said features on and among the units, and so on. Accordingly, it is difficult to draw a narrow borderline between those unit combinations blessed with the mantle of inventive respectability and those not so blessed. Suffice it to say, that the minimal requirement for the includability in the former group is believed to be the presence of the male configurational feature (notch cut) and at least one of the female features (single side-notch or half-notch cut) on separate units, whereby said units could be made to interfit in accordance with present teachings. Preferably, there should be a plurality of more than two of the oppositely sexed units present, but one of each is felt sufficient to bring a set of my structural units within the purview of this invention.

Because of their unusual shapes, the structural units of this invention are impossible of accurate characterization in concise terms. Consequently, shorthand terminology of an ambiguous character standing alone but clear import in context has, for the sake of brevity, been employed in the foregoing description of the units, the distinguishing structural features of the units, for example, thereof being referred to as notch cuts, single side-notch cuts, half-notch cuts and end flap fastening means, respectively (the term "distinguishing" being presently employed in no sense inconsistent with anything previously taught herein). By means of this "shorthand" technique, a simplified disclosure of the geometrical intricacies of my building toy units, completely satisfactory for patent specification purposes, was made possible. For claim recitation purposes, however, the technique leaves something to be desired, and the aforesaid features of the structural units will therefore be identified in terms of structural detail, rather than shorthand terminology, in the claims to follow.

Another semantic peculiarity of the foregoing description of my building toy, not unlike that just discussed, is the absence of a descriptively generic term for the basic toy units themselves, by which is meant the units without their "distinguishing" features. Such an absence was there felt justifiable since, as will be recalled, the building toy was described in terms of milk carton deriva-

tion, rather than geometric shape, of its structural units, the former approach being considered a simpler and easier way of teaching the basic unit shapes than the latter one. As in the case of the "distinguishing" features of the building toy units, and for substantially the reason there applying, the toy's basic units will be hereinafter claimed in language of a more definitive character than was used in the aforesaid description.

Going now from the general to the specific, the basic units of my building toy will be hereinafter described in the claims as tubes which are square in cross section, the term "tubes," as presently contemplated, being intended to encompass tubular members of nonelongate form, as well as such members enclosed at one or both ends. The toy unit feature heretofore referred to as a notch cut will be claimed as a notch defined by end surfaces lying entirely in two planes, said two planes intersecting each other at a right angle, the line of intersection of said two planes being in a first axial plane containing two diametral corners of the tube of notch incidence and being perpendicular to a second axial plane containing the other two diametral corners of said tube, said first axial plane bisecting said right angle, whereby two male tube segments symmetrical about said first axial plane are formed.

Those structural unit features heretofore referred to as single side-notch and half-notch cuts, respectively, will be semantically considered, for claim recitation purposes, as mating female notches for both and one, respectively, 30 of the male tube segments defining a notch cut, said female notches being each so positionally oriented as to receive its mating male members, or member, as the case might be, with the axis of its structural unit of incidence in perpendicular relationship to that of the 35 structural unit of incidence of said male members, or member. The single side-notch and half-notch cuts will accordingly be claimed in language essentially equivalent to this, which, it is felt, will be adequate to identify them with the necessary definiteness and certainty.

40 It will be apparent from a proper understanding of the design and manner of functioning of the male and female features of my toy units, that the aforesaid perpendicular relationship of mated unit axes is not always an axially intersecting one. While, consistently with 45 what has just been emphasized, the end flap fastening means of my building toy units will hereafter be claimed in language of appropriately descriptive character, adequate support for this can, it is believed, be found in the earlier description of the units without the need of 50 further elaboration here.

While it hardly seems necessary so to do, it is pointed out that the term "milk carton" as employed in broad concept in the foregoing description, as well as in the appended claims, is connotative of structural configuration and construction materials consistent with milk cartons, and not function. In other words, by milk cartons, is meant cartons of the type used as milk containers regardless of their actual use (which may be for containing orange juice, fruit punch, etc.). Additionally, 60 while the milk cartons of this invention have been previously identified as being of the "waxed cardboard" variety, that language was used for convenience only and was never intended to be construed in a literal or limitative sense. Thus, the term "milk cartons" as employed above and in the claims following hereinafter includes not only those of the waxed cardboard variety but equivalent ones, such as the more recently employed plastic-coated cartons, as well. In fact, the latter containers are perhaps superior to the older waxed cartons for purposes of my invention.

Finally, to avoid possible misunderstanding from the tenor of the above description, I wish to emphasize that I do not necessarily prefer the milk carton embodiments of this invention over other embodiments thereof. In this connection, as a matter of fact, it is my feeling

that the preferred, and more logical applicability of the invention resides in the manufacture of the structural units of my building toy from suitable plastic materials, preferably of multi-colored design. As I have previously tried to make clear, the emphasis on milk carton derivation of the parts of my toy in the foregoing disclosure was intended purely as a device to simplify the description of the oddly shaped parts and not as an indication of limitability of the invention to such derivation.

It will be apparent from the above that numerous modifications of the described building toy are possible. All of these are within the purview of my invention provided they fall within the scope of the following claims.

I claim:

1. A building toy comprising a plurality of structural units characterized by at least two features which make mating interfit between said units and consequent assembly thereof into aggregates possible, said features being so distributed as to permit such unit interfit and aggregative assembly;
  - (a) said structural units being tubes which are square in cross-section;
  - (b) at least one of said features being a notch in at least one of said tubes, said notch being defined by end surfaces of walls of said one tube, said end surfaces lying entirely in two planes, said two planes intersecting each other at a right angle, the line of intersection of said two planes being in a first axial plane containing two diametral corners of said one tube and being perpendicular to a second axial plane containing the other two diametral corners of said one tube, said first axial plane bisecting said right angle, whereby two male tube segments symmetrical about said first axial plane are formed;
  - (c) and at least one other of said features being means in the form of a female notch in at least one other of said tubes for mating with at least one of said two male tube segments, each such female notch being so positionally oriented on its respective structural unit as to permit mating engagement of its unit with, and in axially perpendicular relationship to, another of said structural units having a notch as defined in sub-paragraph (b).
2. The building toy of claim 1 in which the features which make mating interfit between said units and con-

sequent assembly thereof into aggregates possible comprise a plurality of said notches of the male tube segment forming type described in sub-paragraph (b) and a plurality of said means in the form of mating female notches, as described in sub-paragraph (c), for the male tube segments, at least one of said female notches being receptive of one of said tube segments and at least one being receptive of a pair of said tube segments symmetrical about a common structural unit tube axial plane.

10 3. The building toy of claim 1 in which at least one of the structural unit tubes of sub-paragraph (a) has at least one end enclosed.

15 4. The building toy of claim 1 in which at least one end on each of two of the structural unit tubes of sub-paragraph (a) is enclosed by a flat enclosure disposed perpendicularly to the axis of its structural unit of incidence, said flat end closure being characterized by end flap fastening means adapted to engage similar means on an end enclosure of similar character on a separate 20 structural unit tube when the two end-flap-fastening means-distinguished unit tubes are twisted in end-abutting relationship and in proper positional and twist-directional orientation to effectuate the engagement, whereby said structural unit tubes are thereafter securely held in connectively aligned and end-to-end relationship.

25 5. A building toy in accordance with claim 1, characterized in that at least one notch defining tube wall portion of at least one of the male tube segments formed by a notch as defined in sub-paragraph (b) has a shallow 30 cut running from its edge for a distance less than the depth of the aforesaid notch, said cut also running substantially parallel to the axis of the structural unit tube of its incidence.
